CLAIM

We claim the ornamental design for an end cap for an LED stick, as shown and described.

DESCRIPTION

FIG. 1 is an isometric view of an end cap for an LED stick, showing my new design;

FIG. 2 is front elevation thereof;

FIG. 3 is rear elevation thereof;

FIG. 4 is a right elevation thereof;

FIG. 5 is a top plan view thereof; and

FIG. 6 is a cross-sectional view thereof.

FIG. 7 is an isometric view of a second embodiment of an end cap for an LED stick, showing my new design;

FIG. 8 is front elevation thereof;

FIG. 9 is rear elevation thereof;

FIG. 10 is a right elevation thereof;

FIG. 11 is a top plan view thereof;

FIG. 12 is a cross-sectional view thereof; and,

FIG. 13 is an exploded view thereof.

The left elevation is a mirror image of the right elevation and the bottom plan view is the same as the top plan view, but rotated 180 degrees.
